CLAIM

The ornamental design for a nursery organizer, as shown and described.

DESCRIPTION

FIG. 1 is a perspective view of a nursery organizer showing the new design;

FIG. 2 is a side elevation view thereof;

FIG. 3 is a side elevation view thereof; opposite that shown in FIG. 2;

FIG. 4 is a top elevation view thereof;

FIG. 5 is a bottom elevation view thereof;

FIG. 6 is a end view thereof;

FIG. 7 is a end view thereof, opposite that shown in FIG. 6;

FIG. 8 is a perspective view of the opposite end thereof shown in FIG. 1 illustrating in broken lines supports mounted on the end and folded against the end; and, FIG. 9 is a perspective view thereof similar to that of FIG. 8 illustrating in broken lines the supports in an extended position.

The subject matter illustrated in the drawings in broken lines is not part of the ornamental design.
